UNITED STATES PATENT OFFICE

CARROLL E. LEWIS, OF MINNEAPOLIS, MINNESOTA, ASSIGNOR, BY MESNE ASSIGNMENTS, TO LEWIS AIR CONDITIONERS, INC., OF MINNEAPOLIS, MINNESOTA, A CORPORATION OF DELAWARE

ATOMIZER WITH CLEANING AND FLUSHING ATTACHMENT

Application filed June 13, 1930. Serial No. 460,876.

This invention relates to fluid discharging nozzles and especially to a nozzle adapted to discharge a finely divided whirling conical spray. Such nozzles are extensively used at this time in connection with many types of apparatus and equipment, such as for example, in air conditioning systems, humidifiers, sprayers of all types, milk driers, etc.

It is an object of my present invention to provide a simple and inexpensive nozzle of the type above referred to which will efficiently clean and unclog itself when desired.

In nozzles used for discharging a finely divided spray of water, small ports are usually required within the body of the nozzle for obtaining a swirling of the fluid and these readily become obstructed or clogged due to the presence of small particles of foreign material in the water or other fluid. Moreover, in most available sources of pressure water supply chemicals are present in the water which form a scale within conduits and nozzles through which the fluid passes and this scale in most nozzles often plugs up or obstructs the discharge port.

It is a further object of my invention to provide a nozzle of the class described having means for flushing out the passages and forcibly unclogging and opening the discharge port.

More specifically it is an object of my invention to provide a nozzle of the class described having a body and a longitudinally movable head disposed therein cooperating with the passage in said body to produce a swirling motion upon the water, the movement of said head effecting a thorough flushing of the passage and spiral channels of said head and furthermore serving to forcibly unclog the discharge port.

A further object is to provide a nozzle structure which will minimize, if not entirely eliminate, the formation of scale upon the relatively small spiral channels and other parts which effect the efficiency of the device.

These and other objects and advantages of the invention will be fully set forth in the following description made in connection with the accompanying drawing, in which like reference characters refer to similar

parts throughout the several views wherein:

Fig. 1 is a longitudinal section of the preferred embodiment of my invention with the nozzle or piston head disposed in the normal operating position;

Fig. 2 is a cross section taken on the line 2-2 of Fig. 1 showing the two ports which communicate with the double spiral thread for effecting the swirling action of the fluid discharged;

Fig. 3 shows the application of my device to a humidifier and air conditioner.

In the form of the invention illustrated in Figs. 1 to 3 inclusive my nozzle comprises a straight tubular body indicated as an entire by the letter B having a relatively large axial passage 5 therethrough, being of circular cross section and having a diminished outer end 5a which constitutes an atomizing chamber and which terminates at the outer extremity of body B in a relatively small discharge port 6. The passage at the upper and inner end of body B will be slightly enlarged to receive a suitable packing gland 7 adjustably compressed by means of a packing nut 8 which may have threaded engagement with the exterior of said end of body B. A fluid intake conduit 9 communicates with the medial portion of passage 5, said conduit, as shown, extending laterally with respect to the axis of body B.

A piston or nozzle head 10 is normally disposed longitudinally within the diminished outer portion 5a of the fluid passage, which portion will hereafter be referred to as the atomizing chamber. The nozzle head 10 is shown as in the form of a cylinder of slightly less diameter than atomizing chamber 5a and is provided on its exterior with a relatively coarse, double spiral thread 10a. It will, of course, be understood that a triple spiral thread or any number of spiral threads may be employed. Two or more small grooves 10b extend longitudinally of the nozzle head 10 from the inner end thereof for some distance for forming in conjunction with the atomizing chamber 5a, entrance ports which communicate with the spiral channels formed by the double spiral thread. The communicating grooves or ports 10b

may be conveniently formed by saw-cutting the inner end of the nozzle head or plunger, as clearly shown in Fig. 2.

Nozzle head 10 is preferably slidably connected with a piston rod 11 which extends axially through passage 5 passing through the packing gland 7 at the inner end of the body, the outer end of rod 11 having an enlargement 11a which engages a suitable seat 10 in the outer end of nozzle head 10. A washer 12 may surround the rod 11 at the inner end of nozzle head 10 and a coiled spring 13 is interposed between said washer and collar 14 which is secured to the medial portion of rod 11 to normally position nozzle head 10 at the outer end of the piston rod. The rod 11 may project beyond the upper or inner end of body B and is connected with a suitable operating handle, such as, for example, a lever 15 by which the rod may be actuated both in upward and downward directions.

In the particular application of my nozzle illustrated in Fig. 3 the nozzle is supported in vertical position within the flue 16 of an air conditioner or humidifier, such as the air conditioner disclosed in my co-pending U. S. application S. N. 261,576, filed on March 14th, 1928 entitled "Humidifier and heater." As shown, said flue 16 is provided with a series of arcuate evaporating plates 17 and a unit heater indicated as an entirety by the number 18 sets up a forced circulation of air upwardly through the flue. The discharge end of my nozzle is projected downwardly to discharge a finely divided conical spray in the direction of the upper edges of the evaporating plates. The apparatus, as illustrated, also includes a suitable moisture eliminating device 19 comprising zig zag plates disposed in the upper end of flue 16.

In operation the piston or nozzle head 10 is normally held outwardly by pressure of the fluid, seating against the outer truncated conical extremity of the atomizing chamber 5a. Fluid entering the body of the nozzle passes through passage 5 through the grooves or ports 10b and into the spiral channels formed by cooperation of the double threads 10a with the atomizing chamber 5a. The velocity of the flow of fluid through said spiral channels is relatively high due to the small cross sectional area of the channels and the pressure of the fluid in the enlarged portion of passage 5. Because of this velocity there is practically no chance for chemicals in the fluid to set up a scale upon the spiral threads forming the channels or upon the grooves 10b.

If small particles of foreign material lodge in the ports 10b or in the spiral channels, the same will be readily detected since the spray discharged by the nozzle will not be a perfect conical spray. If such is the case, piston rod 11 may be moved upwardly

or inwardly with respect to the body B by manipulating the lever 15 or other means for operating the same and the nozzle head 10 will accordingly be moved longitudinally from the atomizing chamber 5a into the enlarged or medial portion of passage 5. In such position of the piston the water or other fluid will flush out the spiral channels, the ports or grooves 10b and the atomizing chamber, discharging the foreign material through the discharge port 6.

When it is desired to clean out or unclog the discharge port 6 of the nozzle, the piston rod 11 may be moved longitudinally in an outward direction beyond the point normally positioned when the nozzle head 10 is seated against the outer extremity of the atomizing chamber. This is possible because of the slidable connection between the rod 11 and the nozzle head 10 and since the enlargement 11a at the outer end of rod 11 is axially aligned with discharge port 6 it will be forcibly projected through said port against the tension of coiled spring 13, cutting and removing any scale or material which has accumulated to clog the discharge port. The coiled spring, of course, normally holds the enlargement 11a of the piston rod seated in the outer end of the said head. The spray produced by my nozzle is in the form of a symmetrical whirling cone, the two or more grooves formed by the spiral threads terminating at circumferentially spaced points on the outer end of the head 10. My structure effects a very rapid swirling of the fluid discharged and a substantially perfect spray is assured.

From the foregoing description it will be seen that I have provided a simple but highly efficient self-cleaning nozzle which will not accumulate upon the small ports of the device an incrustation or scale and which may be readily flushed and unclogged without taking the nozzle apart.

By removing the packing nut 8 and the several elements of packing gland 7, the piston or nozzle head and piston rod may be readily removed from the open inner end of body B.

It will, of course, be understood that various changes may be made in the form, details, proportions and arrangement of the parts, without departing from the scope of applicant's invention, which, generally stated, consists in a device capable of carrying out the objects above set forth, and in the novel parts and combinations of parts disclosed and defined in the appended claims.

What is claimed is:—

1. In an atomizer, a body having an axial fluid passage, said passage having a diminished cylindrical outer portion terminating in a relatively small axial discharge port, a cylindrical nozzle head normally seated in the cylindrical portion of said passage and

of substantially similar diameter thereto, a rod extending through said body axially of said passage and having at its outer end slidable connection with said nozzle head,
5 said nozzle head having a substantially helical peripheral groove extending from the inner to the outer end thereof, said body terminating in a discharge port axially aligned with the outer end of said rod and
10 of substantially equal diameter therewith, said rod being slidable in said body for cleaning said port and connected with said nozzle head to retract the same into the enlarged portion of said passage.
15 2. In an atomizer, a body having an axial fluid passage, said passage having a diminished outer portion terminating in a reduced axial discharge port, a fluid supply conduit communicating laterally with said axial passage, a plunger or nozzle head normally seated in the diminished portion of said passage and limited in outward movement by the reduced extremity of said passage forming said discharge port, said plunger being of
20 substantially equal diameter to the outer diminished portion of said passage and having a helical peripheral groove extending from one end to the other end thereof, a rod extending axially through said passage and
25 plunger and projecting through said body for manipulation from the exterior of said body, said rod being slidable both in said body and said plunger and having a connection with said plunger for retracting said
30 plunger into the enlarged portion of said passage, the inner extremity of said rod being axially aligned with and fitting said reduced discharge port to clean the same when said rod is slidably moved inwardly.
35 40 In testimony whereof I affix my signature.
CARROLL E. LEWIS.
